UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

SEWING MACHINE.

Application filed April 8, 1919. Serial No. 288,434.

To all whom it may concern:

Be it known that I, DUDLEY S. SEYMOUR, a citizen of the United States, residing at Oak Park, in the county of Cook, State of Illinois, have invented certain new and useful Improvements in Sewing Machines, of which the following is a description, reference being had to the accompanying drawing and to the figures of reference marked thereon.

The invention relates to new and useful improvements in sewing machines, and more particularly to a looper mechanism including a looper co-operating with a pair of needles to form a vamper stitch.

An object of the invention is to provide a looper mechanism of the above character, wherein the looper is mounted to move in a horizontal plane and is so disposed relative to the line of feed that the lateral or needle avoiding movement of the looper assists in holding the needle loops well back on the looper, so that the needles will both enter with certainty between the body of the looper and the looper thread at a point in advance of both needle loops and without the use of a notched looper and a retainer for the needle thread loops.

A further object of the invention is to provide a looper mechanism of the above character, wherein the looper is so mounted on its carrier that it may be disconnected therefrom and swung to a position for ready access in threading.

These and other objects will in part be obvious and will in part be hereinafter more fully disclosed.

In the drawings which show by way of illustration one embodiment of the invention—

Figure 1 is a front view showing a part of the sewing machine having my improved looper mechanism embodied therein;

Figure 2 is a plan view of the work support;

Figure 3 is a view partly in end elevation and partly in vertical section substantially on the line of feed;

Figure 4 is a view in perspective showing a part of the looper operating mechanism;

Figure 5 is a sectional view on the line 5—5 of Figure 4;

Figure 6 is a sectional view on the line 7—7 of Figure 5;

Figure 7 is a plan view showing the feed, 55 the loopers and the looper operating mechanism; also showing in dotted lines a portion of the work support;

Figure 8 is a similar view but showing the looper carrier disconnected from its support and the loopers moved to position for threading;

Figure 9 is a view partly in side elevation and partly in section showing the looper operating eccentrics and the parts immediately actuated thereby;

Figure 10 is a perspective view showing the feed dog, the needles and the needle guides;

Figure 11 is a view similar to Figure 8. 70 but showing the loopers retracted;

Figure 12 is a view showing more or less diagrammatically, the needle, the feed dog, the loopers and the looper carrier, with the loopers at the rear end of their stroke;

Figure 13 is a front view of the needles and the loopers positioned as in Figure 12;

Figure 14 is a view similar to Figure 12, but showing the loopers at the forward end of their stroke and before their lateral movement to avoid the needles;

Figure 15 is a view similar to Figure 13, but showing the loopers in the position indicated in Figure 14;

Figure 16 is a view similar to Figure 12, 85 but showing the loopers as having moved laterally to open the thread triangle for the entrance of the needles;

Figure 17 is a view similar to Figure 13, but showing the loopers as positioned in 90 Figure 16.

The invention is embodied in a looper operating mechanism for a sewing machine, which is adapted to make a "vamper stitch"—that is, two rows of needle thread 95 loops which are locked by a looper thread loop passing through both needle thread loops and around the bases of the next two needle thread loops. The two needles are preferably set in a line diagonal with the line of feed and the looper is disposed so as to swing in a horizontal plane. The looper is pivoted at a point in rear of the needles and at one side of the line of feed and means is provided for bodily shifting 105 the pivotal support of the looper, so that the looper is given a lateral or needle avoiding movement in a direction forward of the

needles and slightly to the side of the line of feed from which the point of the looper enters the needle thread loop, so that the needle thread loops around the looper at the time 5 of the lateral movement, will be crowded back on to the looper through this lateral movement of the looper combined with the feed of the material, and thus the needle thread loops are held well back on the looper, so as to open the thread triangle for the entrance of both needles between the body of the looper and the looper thread at a point well in advance of both needle thread loops extending about the looper.

15 The invention further includes means for mounting the looper carrier on its support, so that it may be readily disconnected from the support and the carrier shifted so that the looper may be moved from its normal 20 working position underneath the throat plate to a point directly beneath and opening in the cloth plate, which gives ready access to the eyes of the looper for threading the same.

25 The invention will be better understood by a detail reference to the drawings which show one embodiment of the invention. I have shown the invention as embodied in a sewing machine having a base plate 1, on which is mounted a work support 2. The work support 2 is provided with the usual throat plate 3, having needle openings 4, 4 and feed slots 5. The work support is also provided with an opening 6 30 which is closed by a cover plate 7 mounted so as to slide in suitable dovetail grooves formed in the work support. The work support is also provided with a movable section 8, pivoted at 9 and extending along 35 in front of the needles, which section may be swung about the pivot to give ready access to the parts beneath the throat plate. The depending apron 10 of the work support is formed with an opening 11 directly 40 in front of the needles.

45 The sewing machine is also provided with the usual overhanging arm 12, in which is mounted to reciprocate a needle bar 13, which, as herein shown, is provided with two pairs of needles 14, 14 and 15, 15. The material is held on the work support by a presser foot 16, which is of the usual construction. The material is fed across the work support and to the stitching mechanism by a feed dog 17, which is mounted on a feed bar 18. The feed bar 18 is pivoted to a feed rocker 19, which is oscillated by an arm 20 connected to a crank 21 on the end of the main shaft 22. The feed bar 18 is 50 raised and lowered by an eccentric 23, also mounted on said main shaft 22. These parts are of the usual construction, and a further detailed description thereof is not thought necessary.

55 Co-operating with the needles 14, 14, beneath the work support, is a looper 24, and co-operating with the needles 15, 15, beneath the work support, is a looper 25. Both of the loopers 24 and 25 are mounted on the carrier 26. The looper carrier 26 is pivoted 70 at 27 to a support 28 (see Figs. 8 and 11), and the looper support 28 is in turn pivoted to a looper supporting lever 29. The looper supporting lever 29 is mounted to turn on a fulcrum post 30. This fulcrum post is secured to the bed plate 1 of the machine. The forward end of the lever 29 is provided with two spaced lugs 31 and the looper support 28 is in the form of a yoke having two arms 32 and 33, one of which extends below the lugs 31 and the other above the lugs 31, and the arms are pivotally connected to the respective lugs. The pivotal points of the arms are not only in line, but said pivots are also in line with 85 the pivot of the looper carrier proper.

90 The lever 29 is provided with a ball stud at its other end, with which an eccentric strap 34 is connected. This eccentric strap 34 co-operates with an eccentric 35 on the main shaft 22. As the main shaft rotates the lever 29 will be oscillated, and this gives the bodily movements to the pivotal support for the loopers. The looper support 28 is oscillated about its pivots by a link 95 36, which is pivotally connected at one end to a ball stud 40 carried by the looper support (see Fig. 3) and at its other end to a ball stud 41 carried at the outer end of a lever 42. The lever 42 is fulcrumed on a 100 post 43, mounted on the bed 1. Intermediate the ends of the lever 42 is a ball stud 44, to which an eccentric strap 45 is connected. This eccentric strap 45 co-operates with an eccentric 46 on the main shaft 22. 105 As this main shaft rotates the lever 42 will be oscillated and this will in turn oscillate the looper support and move the loopers into and out of the needle thread loops.

110 It will be noted from the drawings that the pivotal connection between the looper support 28 and the lever 29 is at one side of the line of feed, which is clearly indicated by the position of the feed dog, and also in rear of the needles. This pivotal support is also in a line passing between the needles and at right angles to the line of the needles. By this positioning of the pivotal support for the loopers, the looper will move in a direction substantially tangential to the line of the needles—that is, to a horizontal line passing through the two needles.

115 The action of the two loopers is identical and, therefore, in describing the operation 120 only one looper will be referred to in order to avoid confusion.

125 The needles 14, 14 are set diagonal of the

line of feed. The looper when at the rear end of its stroke is in rear of the needles and slightly at one side thereof, as viewed by the operator. The looper moves forward into the two needle loops, as indicated in Figures 14 and 15 of the drawings. After the looper has substantially reached the forward end of its stroke, it is given a lateral movement or needle avoiding movement. 5 This is brought about through the movement of the lever 29. It will be noted that the link 36 and the lever 42 are approaching alinement when the looper is at the forward end of its stroke, see Figure 7, and, 10 therefore, the looper will be given more or less of a dwell at the forward end of its stroke and while the lateral movement of the looper is taking place. In view of the position of the pivotal point of the looper 15 and also of the position of the axis of the lever 29, the looper when moved laterally moves forward, as viewed by the operator, and to the left, see Figure 16. At this time that the looper is moving laterally to avoid 20 the needles, the feed of the material takes place. The combined action of the feed and the looper on the needle thread loops about the looper assists in positioning the needle thread loops, so that both needles will enter 25 between the body of the looper and the looper thread at a point well in advance of the needle thread loops on the looper. 30

In the drawings, I have indicated the looper thread at *l* and the needle threads at 35 *n, n*. In Figure 16 of the drawings, there is shown more or less diagrammatically, the position of the looper thread *l* and the needle thread loops in the needle threads *n, n*, and it will be seen that this lateral movement of 40 the looper, which is also moving backward, and the movement of the feed, as indicated by the arrows, will hold the needle thread loops well back on the looper and open the thread triangle for the entrance of the two 45 needles, thus forming the well known "vamper stitch."

In order to prevent deflection of the needles through the pulling of the threads or the fabric thereon, I have provided needle 50 guards 45' and 46', which co-operate respectively with the pairs of needles 14, 14 and 15, 15. These needle guards are mounted on the feed bar and as the feed bar moves forward the needle guards are brought into 55 proper co-operative action with the needles.

It will be noted from Figures 7 and 8, wherein the throat plate is shown in dotted lines, that the range of action of the looper eyes is well underneath the throat plate and feed dog, which makes it very difficult to thread the loopers. In order to assist in the threading of the loopers, I have provided means whereby the looper carrier may be 60 temporarily disconnected from the looper support and the loopers moved from under- 65

neath the throat plate to a position beneath the opening 6 in the work support. As shown in detail in the drawings, this mechanism consists of the pivotal connection between the looper carrier and the looper support 70 and a latch for locking the looper carrier in a predetermined position relative to said looper support. The looper carrier 26 is formed with a slot 47. A screw 48 passes down through the slot into the looper support and this screw serves to limit the movements of the carrier on the slot. The pivotal connection 27 between the carrier and the support consists of a pivot head 49, see Figure 5, on which the carrier is freely mounted. 75 It is held on its pivot head by a screw 50, which is threaded into the pivot head and small screws 51 carried by the main screw 50 and bearing against the pivot head, limit the inward movement of the screw 50, so 80 that the carrier will have a free movement on the support. The support 28 is formed with a forwardly projecting ledge 52, which has spaced arms 53, 53 between which a latch 54 is adapted to enter to hold the carrier 26 85 in a fixed position relative to the looper support 28. This latch 54 is pivoted at 55 to the carrier and is held depressed by a spring 56 which overlaps the latch and which is secured to the carrier by a screw 57. A handle 90 58 is also secured to the latch to facilitate the raising of the latch. Said latch is also provided with a projecting tail 60, which serves as a stop to limit the upward movement of the latch. The arm 53 has an inclined face 61. When it is desired to release 95 the carrier to swing the loopers to threading position, the handle 58 is raised, lifting the latch, and then the carrier is swung about its pivot point 27 until further movement is 100 prevented by means of the screw 48 and slot 47. This brings the loopers underneath the opening 6, as clearly shown in Figure 2, wherein the loopers are in threaded position. After the loopers have been threaded, then 105 the handle for the carrier may be grasped and moved in the opposite direction, and the latch will move up the inclined surface 61 and drop between the arms 53, locking the carrier in operative position. Each looper 110 is provided with an eye 62, adjacent its point, and also with an eye 63 at the heel of the looper. The looper thread is led from a supply through suitable guides and tensions 115 and then to thread eyes 64. After passing 120 through the thread eyes 64, the looper thread is led to thread eyes 65 in an arm mounted on the lever 29 and from these eyes 65 the looper threads pass to the eyes 63 at the 125 heels of the loopers and then to the eyes 62 of the loopers. The thread eyes 64 and 65 moving with the looper carrier serve to take care of the slack in the looper thread and also to assist in the drawing up of the looper threads to properly set the stitches. 130

It is obvious that minor changes in the details of construction and the arrangement of the parts may be made without departing from the spirit of the invention, as set forth in the appended claims.

Having thus described my invention, what I claim as new and desire to secure by Letters Patent is:

1. In the combination of a feeding mechanism, a pair of needles arranged in a line diagonal to the line of feed and a threaded looper adapted to cooperate with said pair of needles, means for pivotally supporting said looper whereby it moves in a horizontal plane and tangentially to a line diagonal to the line of feed and parallel to the line containing the needles as it enters the needle thread loops, means for shifting said support in a horizontal plane toward the needles while the looper is in the needle thread loops whereby the face of the looper will operate to draw the needle thread loops about the looper to one side so as to insure both needles entering a thread triangle in advance of the needle thread loops.

2. In combination with a feeding mechanism, of a pair of needles arranged in a line diagonal to the line of feed, a threaded looper adapted to cooperate with said pair of needles, means for pivotally supporting said looper whereby it moves in a horizontal plane and tangentially to a line diagonal to the line of feed and parallel to the line containing the needles as it enters the needle thread loops, means for shifting said support in a horizontal plane toward the needles while the looper is in the needle thread loops whereby the face of the looper will operate to draw the needle thread loops about the looper to one side so as to insure both needles entering a thread triangle in advance of the needle thread loops, said looper being disposed so as to move in rear of the needles when entering the needle thread loop.

3. The combination of a feeding mechanism, a pair of needles arranged in a line diagonal of the line of feed, a looper co-operating with said needles, means for pivotally supporting said looper whereby the same moves in a horizontal plane and in a path tangential to the diagonal line of the needles and in rear of the needles when entering the needle thread loops, means for moving said pivotal support for carrying the looper to a position in front of the needles while in the needle thread loops, whereby the face of the looper which inclines to the line of feed assists in carrying the needle thread loops to one side of the path of the needles so as to insure both needles entering the looper thread loop in advance of the needle thread loops.

4. The combination of a feeding mechanism, a pair of needles arranged in a line diagonal of the line of feed, a looper co-

operating with said needles, means for pivotally supporting said looper, whereby its point moves in a horizontal plane and in a path tangential to the diagonal line containing the needles and in rear of the needles 70 as the looper enters the needle thread loops, and means for moving said pivotal support toward and from the needles for carrying the looper to the opposite side of the needles while in the needle thread loops and while 75 the feed is moving the fabric, whereby the combined action of the feed of the fabric and the face of the looper on the needle thread loops serves to hold the needle thread loops well to one side of the path of both 80 needles.

5. The combination of a feeding mechanism, a pair of needles arranged in a line diagonal of the line of feed, means for operating the needles, a looper co-operating 85 with the needles, means for pivotally supporting said looper, whereby the point of the looper moves in a horizontal plane and from a position at one side of the line of feed across the line of feed as it enters the needle thread loops, said pivotal support for the looper being arranged on the opposite side of the line of feed from the point of the looper when retracted, and means for moving said pivotal support toward and from 95 the needles for carrying the looper to the opposite side of the needles while in the needle thread loops.

6. The combination of a feeding mechanism, a pair of needles arranged in a line 100 diagonal of the line of feed, means for operating the needles, a looper, a looper support, means for pivotally supporting said looper support, whereby the looper moves in a horizontal plane, said pivotal support for the 105 looper being disposed at one side of the line of feed and in a line passing between the needles and substantially at right angles to the diagonal line containing the needles, and means for bodily moving said pivotal support for carrying the loopers from one side 110 of the needles to the other.

7. The combination of a feeding mechanism, a pair of needles arranged in a line diagonal of the line of feed, a horizontally 115 moving looper co-operating with the needles, a support for said looper, a lever on which said support is pivotally mounted, means for oscillating said support for giving a lateral movement to the looper, means for 120 oscillating the support on the lever for moving the looper into and out of the needle thread loops, said last named means including a lever, a link connecting the lever to the looper support, and means for oscillating 125 the lever, said lever and link being so disposed as to be substantially in a line when the looper is at the forward end of its stroke.

8. The combination of a feeding mechanism, a needle, a looper moving in a horizon- 130

tal plane and co-operating with said needle, a yoke-shaped support for said looper, a lever having spaced lugs pivotally attached to said yoke-shaped support, means for oscillating the lever, and means for oscillating said looper support on its pivotal connection with said lever.

9. The combination of a main shaft, a feeding mechanism operated from said main shaft, a looper mechanism operated from said main shaft and including a lever pivoted to swing in a horizontal plane and having spaced lugs, a yoke-shaped support straddling said shaft and pivotally connected to the spaced lugs on said lever, a looper carried by said looper support, and means for oscillating said looper support.

10. The combination of a main shaft, a feeding mechanism operated from said main shaft, a looper mechanism operated from said main shaft and including a lever pivoted to swing in a horizontal plane, and having spaced lugs, a yoke-shaped support straddling said shaft and pivotally connected to the spaced lugs on said lever, a looper carried by said looper support, and means for oscillating said looper support, said last named means including a lever, means for oscillating the lever from the main shaft, a link connecting the lever with the looper support, said link and lever to which it is connected being substantially in a line when the looper is at the forward end of its stroke.

35 11. The combination of a work support, a throat plate carried by said work support, a looper mechanism disposed beneath the work support and including a looper moving in a horizontal plane and in a path extending beneath the throat plate, a carrier on which said looper is mounted, an oscillating support, means for oscillating said support, means for pivotally mounting said carrier on said oscillating support, a 40 spring controlled latch for holding the carrier in a predetermined position on said support, and means for limiting the move-

ment of the carrier when released from the support.

12. The combination of a work support, 50 a throat plate carried thereby, a looper mechanism located beneath the work support and including a horizontally moving looper, a carrier on which said looper is mounted, an oscillating support for said carrier, said carrier being pivoted to said oscillating support, a stop for limiting the movement of the carrier on said support, a spring controlled latch for locking the carrier to the support with the looper in 55 normal position.

13. The combination of a work support, a throat plate carried thereby, a looper mechanism located beneath the work support and including a horizontally moving 65 looper, a carrier on which said looper is mounted, an oscillating support for said carrier, said carrier being pivoted to said oscillating support, a stop for limiting the movement of the carrier on said support, a spring 70 controlled latch for locking the carrier to the support with the looper in normal position, said support having a cam face co-operating with the latch, whereby the latch will automatically lock the looper carrier when the 75 same is shifted to normal position.

14. The combination of a looper support, a looper carrier pivotally mounted on said support, spaced lugs, a latch adapted to engage between said spaced lugs for holding 80 the looper in normal position relative to the support, a spring for holding said latch between the lugs, a handle for lifting the latch, said support having a cam face on which said latch rides to lift the same for 85 causing the latch to automatically engage between the lugs when the carrier is shifted to bring the looper to normal position.

In testimony whereof, I affix my signature, in the presence of two witnesses.

DUDLEY S. SEYMOUR.
